[57] CLAIM

The ornamental design for a fish-shaped tackle container and carrying case, as shown and described.

DESCRIPTION

FIG. 1 is a left side elevational view showing the first embodiment of my new design;

FIG. 2 is a right side elevational view showing the first embodiment of my new design the strap is shown broken away for convenience of illustration;

FIG. 3 is a top plan view thereof;

FIG. 4 is a bottom plan view thereof;

FIG. 5 is a front elevational view thereof;

FIG. 6 is a rear elevational view thereof;

FIG. 7 is a rear perspective view thereof;

FIG. 8 is a front perspective view thereof, with an access door shown in the open position;

FIG. 9 is a left side elevational view showing the second embodiment of my new design;

FIG. 10 is a right side elevational side view showing the second embodiment of my new design;

FIG. 11 is a top plan view thereof;

FIG. 12 is a bottom plan view thereof;

FIG. 13 is a front elevational view thereof;

FIG. 14 is a rear elevational view thereof;

FIG. 15 is a rear perspective view thereof with an access door closed the strap is shown broken away for convenience of illustration; and,

FIG. 16 is a rear perspective view thereof, with the access door shown in the open position the strap is shown broken away for convenience of illustration.
